CAN CLOSING MACHINE

Howard B. Peterson, San Francisco, Calif., assignor to American Can Company, New York, N. Y., a corporation of New Jersey

Application May 9, 1940, Serial No. 334,256

4 Claims. (Cl. 113—24)

The present invention relates to can closing machines and the like and has particular reference to a simplified machine in which the can lifter pad is independently actuated and has no mechanical connection with the can closing head, the lifter pad and the closing head being operated by separate electric motors.

In the usual can closing or seaming machine the can lifter pad and the closing head are preferably mechanically interconnected and actuated and in such a machine adjustment of the lifter pad to accommodate cans of different heights is manually effected. It has been found that where such a machine is used for a number of varying heights of cans the frequent changing of the machine to adapt it to a particular can height is quite a problem in a small cannery.

The present invention contemplates overcoming this difficulty by eliminating the mechanical connection between the machine closing head and the lifter pad and independently driving them with electric motors, the lifter pad motor being preferably of the high torque type. No adjustment or change over is needed for cans of varying heights when such an idea is used, thus providing a simple and flexible machine for small canners.

An object, therefore, of the invention is the provision of a can closing machine wherein the can lifter device is actuated independently of the machine closing head and is free from any mechanical connection therewith so that flexibility in machine operation will result.

Another object is the provision, in such a can closing machine, of can support devices which do not require manual adjustment for can heights so that cans of varying heights may be readily closed without any preparatory setting.

Another object is the provision of a can closing machine of this character wherein the clamping effect of the lifter pad operating through the can to the closing head may be controlled to exert a predetermined pressure on the can during the closing operation independently of can height.

Another object is the provision of such a can closing machine utilizing separate electric motors for independently actuating and controlling the operation of closing head and lifter pad.

Numerous other objects and advantages of the invention will be apparent as it is better understood from the following description, which, taken in connection with the accompanying drawings, discloses a preferred embodiment thereof.

Referring to the drawings:

Figure 1 is a front elevation of a can closing machine embodying the instant invention, parts being broken away and parts shown in section; 5 Fig. 2 is a side elevation and sectional view of the machine shown in Fig. 1, with parts broken away;

Fig. 3 is an enlarged sectional view of the can closing head used in the machine; and 10 Fig. 4 is a wiring diagram of the electric apparatus used in the machine.

As a preferred embodiment of the invention the drawings disclose a sheet metal can closing machine which includes an independently actuated can lifter device A (Fig. 2) for lifting a can B having a loosely applied cover C into an independently actuated seaming head unit D for sealing the cover on the can. The lifter device and the seaming head unit are carried on a vertical column 11 (Figs. 1 and 2) which constitutes the main frame of the machine.

The lifter device A includes a flat horizontal lifter pad 12 (see also Fig. 1) which is secured to the upper end of a vertical rod 13 carried in a pair of spaced upper and lower bearings 14 formed in a gear casing 15. Casing 15 is bolted to the front of the column 11 and is disposed in a slideway 16 formed in the column. The lifter pad is formed with a guide 18 for centralizing a can A when it is manually positioned on the pad for sealing.

The lifter pad 12 is raised vertically to bring the positioned can B into the seaming head D and for this purpose is provided with a gear rack 21 formed on a sleeve 22. The sleeve surrounds and is secured to the vertical rod 13 intermediate its bearings 14. The rack meshes with a pinion 23 mounted on a shaft 24 carried in suitable bearings formed in a side of the gear casing 15 and in a vertical web 25 formed therein.

The shaft 24 also carries a gear 27 which meshes with a pinion 28 mounted on a shaft 29 carried in suitable bearings formed in the sides of the gear casing. This latter shaft extends through the casing web 25 and carries a large gear 31 which meshes with a driving pinion 32. The driving pinion is mounted on a driving shaft 33 which is carried in suitable bearings formed in the sides of the gear casing. This driving shaft 33 is the rotor shaft of a high torque reversible electric motor 35 which is bolted to the gear casing 15.

Hence when the motor is excited it rotates the driving pinion 32 and through it the gear train just explained and thus raises or lowers the lifter

pad 12 and the can B carried thereon relative to the seaming head unit D. The actuation of the motor is preferably effected through electric apparatus indicated in the wiring diagram in Fig. 4 which will be hereinafter explained and which includes a start and stop switch 36 which is secured to the gear casing 15. A switch lever 37 is provided on the switch for manually actuating it.

The can seaming head unit D is disposed directly above the lifter pad 12 and is located in a housing 41 which is secured to the front of the column 11 and to an overhanging bracket extension 42 of the column. There are many suitable types of seaming head units used in standard closing machines which may be used here and the instant invention is equally well adapted for use with any of these types.

The drawings show one form of seaming head unit of the character disclosed in United States Patent 1,716,618, issued June 11, 1929, to Harvey L. Bryant on Can closing machine. This head unit includes a vertical tubular support member 45 (Fig. 3) the upper end of which is tightly clamped in a clamp block 46 formed in the column bracket extension 42. The support member is adjustably held against vertical displacement by a locknut 47 which is threaded on the upper end of the member and which is carried in a locking block 48 bolted to the bracket extension 42 and rests in a recess 49 formed therein.

The support member 45 carries a seaming head casing 51 which surrounds the lower end of the member and is fully contained in the housing 41. The casing is secured to a ring bevel gear 52 having spider arms 53 which radiate from a central hub 54. The hub 54 contains a ball bearing 55 which is mounted on the support member 45. The ball bearing is locked in place against vertical displacement relative to the support member by an upper locknut 56 threaded on the member and by a worm 57 which is keyed on the member. The worm is held in a fixed vertical position by a lower threaded locknut 58.

The bottom of the casing 51 is formed with a central hub 61 which surrounds the lower part of the tubular support member 45 and rests on a collar 62 formed on the lower end of the member. Below its collar 62 the member carries a stationary can chuck 63 which is adapted to receive the can B and its cover C when they are lifted into can closing position.

The head casing 51 is adapted to be rotated around the chuck 63. To effect such a rotation there is provided an electric motor 65 (Fig. 2) having a self-contained brake. The motor is bolted to the column 11. The rotor shaft of the motor carries a bevel pinion 66 which meshes with and drives the head ring gear 52.

In this seaming head unit the seaming of the can cover C to the can B is preferably performed, while the head rotates, by an interfolding of flange parts formed on the cover and on the can. This folding operation is performed by a plurality of seaming rollers 68 (Fig. 3) which are mounted in slides 69 carried in radial slideways 71 formed in the bottom of the head casing 51. There are preferably four of these rollers, two first operation rollers and two second operation rollers and these two sets of rollers are spaced ninety degrees apart.

Each seaming roller slide 69 is connected by a link 72 to the lower end of a vertical actuating lever 73. Each lever is loosely mounted on an eccentric 74 formed on a pivot pin 75 which is

carried in suitable bearings formed in the head casing 51. The pivot pins also carry worm gears 76 which mesh with the stationary worm 57.

The upper ends of the actuating levers 73 extend above the head casing 51 and carry cam rollers 77 which operate on a stationary pattern cam 78 which surrounds the head supporting member 45 and which is secured to the overhanging bracket extension 42 of the column 11. A coiled spring 79 extending around the head and seated on grooved rollers 81 carried on the upper ends of the actuating arms, maintains the cam rollers 77 in operating engagement with the cam 78.

Hence as the seaming head rotates, the cam rollers 77 follow around the stationary pattern cam 78 and rock the actuating arms 73 in the proper direction for shifting the slides 69 toward and away from the stationary chuck 63 so that the seaming rolls 68 will follow the contour of the chuck.

During this rotation of the head the stationary worm 57 effects a slow rotation of the gears 76 and this revolves the eccentric 74 in the actuating arms 73 and thus brings the seaming rollers 68 into can seaming position relative to the chuck at the proper time and again shifts them out of seaming position at the end of the seaming operation. It is these motions and rollers that effect the sealing of the cover C to the can B.

A knockout plate 85 (Fig. 3) is provided in the seaming head and this plate is located below the chuck 63 adjacent a recess 86 formed therein. The plate is secured to the lower end of a rod 87 which extends up through the middle of the head support member 45. A tip member 91 having an annular shoulder 92 is threaded to the upper end of the rod 87.

The shoulder 92 of the tip 91 normally engages the pointed inner end of a pawl 94 which is mounted on a pivot pin 95 secured in a starting switch lever 96 associated with the seaming head motor 65. The pawl is pressed outwardly toward the shoulder by a compression spring 97 which is interposed between the inner end of the pawl and a step section 98 formed in the switch lever. A setscrew 99 located in the outer end of the lever engages the step section 98 and controls outward displacement of the pawl.

The switch lever 96 is mounted on a pivot pin 101 carried in a bracket 102 formed on the clamp block 48. A tension spring 103 keeps the lever under tension and maintains the pointed end of the pawl 94 in engagement with the tip shoulder 92. One end of this spring is secured to the lever while its opposite end is connected to the bracket 102. The lever extends out over a normally open start switch 105 associated with the seaming head motor 65 and this switch is formed with a movable element 106 which is engageable by an adjustable setscrew 107 carried in the lever. The lever is also formed with a handle 108 for manual operation of the start switch if desired.

When a can B is lifted up into the seaming head unit D for sealing, its cover C first engages the knockout plate 85 and forces it up with the travel of the can toward the chuck 63 of the seaming head. This action raises the knockout plate rod 87 and its tip member 91. As the tip moves up its shoulder 92 raises the pawl 94 and thus rocks the switch lever 96 so that the setscrew 107 engages the movable element 106 of the start switch 105. This closes the switch.

Closing of the start switch takes place just as the can and its cover are fully seated against the

seaming head chuck 63. The closing of the switch starts the seaming head motor 65 with the result that the seaming head begins to rotate for the can closing operation. This takes place while the lifter plate motor 35 holds the can and its cover clamped tightly against the chuck.

Near the top of the up stroke of the knockout plate rod 87 the switch lever pawl 94 rides off the shoulder 92 of the tip 91 and falls down alongside of the tip. This action permits the start switch lever 96 to rock back into its original position and the start switch 105 is immediately opened. In other words closing of the switch is only of momentary duration. The motors, however, continue to operate through holding circuits. This will be fully explained in connection with a consideration of the wiring diagram in Fig. 4.

The seaming head D rotates through a predetermined number of revolutions to complete the can closing cycle, as is usual in such seaming heads, and at the completion of the cycle both the lifter pad and seaming motors cease operation. Stopping of the motors is brought about by a normally closed stop switch 111 (Fig. 2) which is secured to the column 11 and which is momentarily opened by a switch arm 112 actuated by the seaming head.

The stop switch arm 112 is mounted on a pivot pin 113 carried in a bracket 114 formed on the machine column 11. The outer end of the arm carries an adjustable setscrew 115 which is adapted to engage a movable element of the switch when the arm is actuated. The inner end of the arm projects through an opening 117 formed in the machine column 11 and terminates adjacent the outer surface of the seaming head casing 51.

The inner end of the arm 112 is engageable at the end of the seaming cycle by a roller 121 (Fig. 3) which is carried on a leg 122 of a bell crank 123 mounted on a pivot pin 124 supported in the head casing 51. A second arm 125 of the bell crank extends inwardly of the head casing and carries a roller 126 which is in the path of travel of a high spot 127 formed in a peripheral cam 128. The cam is carried on one of the seaming roller actuating arm pivot pins 75.

The arm 122 of the bell crank 123 is spring held against centrifugal forces so as to be disposed within the seaming head casing 51, and as the head rotates during a seaming cycle the cam 128 is rotated by the gear 76 which is secured to its pivot pin 75. The gear 76 makes one revolution for each seaming cycle. Hence at the end of the cycle the high spot 127 of the cam 128 comes into engagement with the roller 126 on the bell crank and this rocks the latter so that its arm 122 and the roller 121 carried thereon is projected out of the head casing and into the path of the switch arm 112. When the head makes its last revolution in the seaming cycle the extended roller 121 engages the switch arm and momentarily rocks it into switch opening position. This stops the motors 35, 65 and the brake on the sealing head motor 65 immediately stops further rotation of the seaming head.

The closed can is lowered from engagement with the seaming head chuck 63 by re-starting the lifter pad motor 35 in a reverse direction. As the can moves down with the descending lifter pad 12, the knockout plate 85 follows down with it until the plate has reached its lower limit of travel as shown in Fig. 3. This descent of the plate moves the rod 87 and its tip 91 down into their original positions and during this descent

the spring-held switch pawl 94 remains in engagement with the side of the tip until the shoulder 92 comes adjacent the pawl. The pawl then snaps over the shoulder into the position shown in Fig. 3 in readiness for a subsequent operation of the seaming head starting switch.

The wiring diagram of the various electric circuits used to interconnect the motors 35, 65, as shown in Fig. 4, will now be explained. In this diagram the lifter pad motor 35 is controlled primarily by four circuits, a can raising or lifting circuit R, holding circuit S, an operating circuit T, and a can lowering or reverse circuit U. Electric energy for exciting the motor 35 is received preferably from a three phase power line which includes main lead wires 151, 152, 153 which extend through a normally closed main service switch 154 and end at terminals 155, 156, 157 located in a receiving relay box 158.

The lifter pad motor 35 is first set in operation by the manually operated switch 36 (see also Fig. 1). This switch is formed with a movable element 161 (Fig. 4) which is attached to the switch handle 37. In the up position of the handle the movable element 161 closes against a pair of upper contacts 162, 163 and in the down position it closes against a pair of lower contacts 164, 165. When the handle is in a neutral position the movable element is out of engagement with all contacts and therefore the switch is open.

The upper contact 162 of the lifter control switch 36 is connected by way of a wire 171 to the main energy supply terminal 156 in the relay box 158. The other upper contact 163 is connected by way of a wire 172 to a relay coil 173 and this coil is connected by a wire 174 to the main supply terminal 157. This constitutes the normally open can lift circuit R.

Hence when the lifter control switch 36 is closed in the up position as when first starting the machine after placing a can B on the lifter pad 12, electric energy from the main lead wires 151, 152, 153 flows through the R circuit and energizes the relay coil 173. Energization of the coil closes a series of relay switch elements 176, 177, 178. These switch elements contact with the wire terminals 155, 156, 157 and with a cooperating set of terminals 181, 182, 183 which are connected by wires 184, 185, 186 to a torque adjusting rheostat 187. The lift motor 35 is connected to this rheostat by wires 188, 189, 190.

Closing of the relay switch elements 176, 177, 178 establishes the motor operating circuit T and hence electric energy direct from the main lead wires 151, 152, 153 is transmitted through the rheostat to the motor to effect its rotation. It is this rotation of the motor that raises the lifter pad 12 and thus brings the can B and its cover C into engagement with the seaming head unit D. When fully engaged, the motor 35 stalls, since it is not sufficiently powerful to overcome the resistance of the can, and this stalling action clamps can and cover tightly against the head where they remain held during the seaming operation. The clamping pressure may be controlled by adjustment of the motor torque through the rheostat 187.

It will be remembered that when the can and its cover near the uppermost raised position just prior to engagement with the seaming head unit D, it pushes up the knockout plate 85 and thereby momentarily closes the seaming head motor start switch 105. Closing of this switch brings into play a starting circuit V, a holding circuit W, and a motor operating circuit X, all of which

serve the seaming head motor 65. This is shown at the left in Fig. 4. These circuits preferably receive electric energy from a separate source from that of the previously described circuits. Such latter energy is transmitted over main lead wires 201, 202, 203. These wires extend through a normally closed service switch 204 and end at terminals 205, 206, 207 located in a relay box 208.

Terminal 205 is connected by a wire 211 to 10 the head start switch 105. The switch is also connected by a wire 212 to a relay coil 213 which in turn is connected by a wire 214 to the normally closed head stop switch 111. This stop switch is connected by a wire 215 to a normally closed thermal overload switch 216 which is also connected by a wire 217 to the lead wire terminal 206. This constitutes the starting circuit V and it is such a starting circuit that is established when the head start switch 105 is momentarily closed.

Establishment of the head starting circuit V energizes the relay coil 213 and this shifts a plurality of relay switch elements 221, 222, 223, 224, 225 into closing position with adjacent terminal contacts, which will now be described. Switch elements 222, 223, 224, close against the main lead wire terminals 205, 206, 207 and against co-operating terminal contacts 227, 228, 229. These latter contacts are connected by wires 232, 233, 234 leading into the seaming head motor 65. Closing of these switch elements establishes the head motor operating circuit X and hence energy from the main lead wires 201, 202, 203 is transmitted directly into the head motor for turning the seaming head through its predetermined cycle.

The relay switch element 225 closes against a pair of terminal contacts 238, 239 located in the relay box 208. These contacts 238, 239 are connected by respective wires 241, 242 to the contacts 162, 163 of the lifter motor switch 36. This constitutes the lifter motor holding circuit S referred to above and closing of the relay switch element 225 with its contacts 238, 239 establishes this circuit and thereby cuts out the lifter motor start switch 36 so that the lifter motor 35 will remain excited after its start switch is opened.

Since closing of the seaming head motor start switch 105 is only of momentary duration, a holding circuit is provided to maintain all the other circuits R, S, T, V, X after they have been established. This holding circuit is the circuit W and it is established by the closing of the relay switch element 221. This element closes against a pair of contacts 245, 246. Contact 245 is connected by a wire 247 with the main lead wire terminal 205 and contact 246 is connected by a wire 248 to the relay coil 213.

Such a holding circuit cuts out the head motor start switch 105 and transmits energy direct from the main lead wire 201, through terminal 205, wire 247, contact 245, closed switch element 221, contact 246, wire 248, coil 213, wire 214, stop switch 111, wire 215, overload switch 216, wire 217, terminal 206, returning to the main lead wire 202. Energy passing along this circuit keeps the coil 213 energized after the start switch 105 opens and thereby keeps the relay switch elements in engagement with their terminal contacts.

Upon completion of the seaming cycle as hereinbefore explained, the head stop switch 111 is momentarily opened and this breaks the head holding circuit W. This de-energizes the relay 75

coil 213 and hence permits the relay switch elements 221, 222, 223, 224, 225, to move away from their terminal contacts under spring pressure. Such an action breaks all of the remaining circuits and hence operation of both motors 35, 65 ceases. The brake in motor 65 arrests further carry-over motion of the seaming head so that it will be in its proper starting position for a subsequent seaming operation.

After breaking of the motor circuits the sealed can is moved away from the seaming head unit D by a lowering of the lifter pad 12 as hereinbefore mentioned. This is brought about by restarting the lifter motor 35 in a reverse direction. For this purpose the lifter starting switch handle 37 is moved down into the lower dotted position as shown in Fig. 1. This is the down position of the switch 36.

In this down position of the lifter motor start switch 36 its movable element 161 (at the right in Fig. 4) closes against the lower contacts 164, 165. Contact 164 is connected by a wire 251 to a relay contact 252 which in turn is connected by a wire 253 to the main lead wire terminal 155. Switch contact 165 is connected by a wire 255 to a relay coil 256. The coil is also connected by a wire 257 to a relay contact 258 which in turn is connected by a wire 259 to the main lead wire terminal 156. This constitutes the can lowering circuit U and when the starting switch element 161 connects the lower contacts 164, 165, the circuit is completed and energy flows from the main lead wires 152, 153 into the relay coil 256 which is thereupon energized.

Energization of the relay coil 256 shifts a plurality of relay switch elements 261, 262, 263 against contacts which connect the main lead wires 151, 152, 153 with the lift motor 35. The motor is thus excited and rotates in reverse order and the lifter pad 12 moves down. A consideration of the wire connections necessary to complete the motor circuit follows.

Relay switch element 261 closes against the terminal contact 252 and a co-operating contact 265 which is connected by a wire 266 to the relay contact 183, and thence by way of the motor lead wire 190. Relay switch element 262 closes against the terminal contact 258 and a co-operating contact 267 which is connected by a wire 268 to the relay contact 182 and thence by way of the motor lead wire 188. Relay switch element 263 closes against a pair of contacts 271, 272. Contact 271 is connected by a wire 273 to the main lead wire terminal 157 and contact 272 is connected by a wire 274 to the relay contact 181 which joins with the motor lead wire 189. This therefore completes the motor circuit through its three phase wire leads.

When the descending lifter pad 12 reaches its original lowermost position further movement is arrested by engagement with the upper rod bearing 14 and the lifter pad is brought to a sudden stop. This stalls the motor 35. The switch 36 may then be manually opened to cut off the current and this de-energizes the relay coil 256 and thus breaks the motor reverse circuits. This completes the cycle of the machine operation and the sealed can is thereupon removed from the lifter pad to make way for the next can to be closed.

It is thought that the invention and many of its attendant advantages will be understood from the foregoing description, and it will be apparent that various changes may be made in the form, construction and arrangement of the parts with-

out departing from the spirit and scope of the invention or sacrificing all of its material advantages, the form hereinbefore described being merely a preferred embodiment thereof.

I claim:

1. In a can closing machine, the combination of a rotatable seaming head including a chuck for securing covers to cans to close them, a support movable relative to said head for supporting a can to be closed, a high torque reversible electric motor, gearing directly connecting said motor and said support, means to operate said motor to cause said support to clamp and hold the can against said chuck during the can closing operation so that cans of various heights may be readily closed without adjustment of said support, and means for varying the torque of said motor to obtain a predetermined pressure on the can during the closing operation.

2. In a can closing machine, the combination of a rotatable seaming head including a chuck for securing covers to cans to close them, an electric head motor for rotating said head through a can closing cycle, a support movable relative to said head for supporting a can to be closed, a reversible high torque electric motor geared directly to said support for actuating the latter to bring the can thereon into engagement with said chuck and to remove the closed can therefrom, electric devices connecting said motors for maintaining said torque motor in actuation during the operation of the head motor, said torque motor pressing the can against said chuck with a predetermined pressure and said head motor rotating said head while the can is being closed, and electric means operable by said head at the completion of said can closing cycle to stop operation of both of said motors.

3. In a can closing machine having a rotatable seaming head for securing can covers to cans to close the same and having means for rotating said head, the combination of a support movable relative to said head for holding a can to be closed, means for moving said support toward the head to carry a can of any one of various heights into closing position relative to the head and for holding the can in said position during a can closing cycle, means included in said head and engageable by a can on said support when the latter is in can closing position for actuating said head rotating means, to rotate the head through a can closing cycle to secure a cover to the can, and means for moving said support and the closed can thereon away from said seaming head.
4. In a can closing machine, the combination of a rotatable seaming head for securing can covers to cans to close the same, means for rotating said head, a can support movable relative to said head for holding cans to be closed, a high torque electric reversible motor geared directly to said support for moving the latter toward and away from the head to carry a can into and out of closing position relative thereto, means responsive to the movement of a can as it is brought into can closing position by said support for actuating said rotating means to institute rotation of the head for a can closing cycle to secure a cover to the can, and electric devices energized by the actuation of said rotating means for holding said motor and said head rotating means in operation during the can closing cycle.

HOWARD B. PETERSON
